UNITED STATES PATENT OFFICE.

ROBERT C. MATHERS, OF WYOMING, NEW JERSEY, ASSIGNOR TO WESTERN ELECTRIC COMPANY, INCORPORATED, OF NEW YORK, N. Y., A CORPORATION OF NEW YORK.

ELECTRIC-CURRENT TRANSMISSION.

Application filed October 9, 1923. Serial No. 667,437.

This invention relates to the transmission of electric currents, and aims to provide improvements in the two-way transmission of such currents, for instance in the two-way repeating of telephonic currents.

It has heretofore been proposed to employ switching means responsive to voice currents or other transmission for controlling repeating means in order that, when the repeating means is in use, it may give good transmission in one, and only one, direction at a time. The time required for the switching means to operate in response to the transmission tends to diminish the effectiveness of its function, as for instance, by causing undue loss in articulation because of the failure of the contacts of the switching means to condition a signaling path for efficient transmission in the desired direction in time to transmit properly the initial part of the message incident upon the path. It has been suggested that such a tendency may be overcome by the proper use of a so-called delay circuit, consisting, for example, of a low-pass filter type of structure comprising recurrent sections each having a series arm containing lumped inductance and a shunt arm containing lumped capacity. For instance, it has been proposed to insert such a circuit, which has the property of appreciably delaying the propagation of signaling currents therethrough, in the part of the signaling path between the point in the path at which the switching means responsive to transmission derives energy from the path and the point in the path at which the switching means conditions the path for efficient transmission.

In accordance with this invention, in order to diminish the requisite delay time of delay circuits in such uses, the switching means is caused to accomplish its function immediately upon the opening of a contact, the opening of the contact being accomplished in response to signaling currents and without delay due to other mechanical movement. The reason why this procedure results in diminution of the requisite delay time of the delay circuit is that the time required for a relay to break, or open its contact, is far less than the time consumed in the travel of the armature to a make, or closing contact.

It has been discovered that where high speed switching means, or other quick op-

erating means, responsive to transmission is used for controlling a repeating circuit in order that when the repeating circuit is in use it may give good transmission in one and only one direction at a time, the operation of the controlling means may be deleteriously effected by transient energy which may emerge from the line connected to the output of the repeater after the input to that line has ceased. In general, when the input transmission to the line ceases some energy will return from it and will enter the output of the repeater. There are various factors which may cause energy sent out by a repeater to reenter it. For example, the energy may be reflected from terminal apparatus; or may be stored in the line and fed back into the repeater, or stored in terminal apparatus and fed back into the line and repeater, upon cessation of input from the repeater to the line; or may be sent back into the line and repeater by repeaters such as ordinary, or standard, 22-type repeaters to which the line may be connected. An extreme case is that of a repeated line with excessive echo currents. In the case of a voice controlled telephone repeater, for instance, as far as the repeater and its controlling apparatus are concerned this transient returned energy acts in the same way as do voice currents coming from the listener. Consequently, if the energy of these transient returned currents is sufficient they may seriously interfere with the operation of the controlling means for the repeating circuit. For example, in the case where the controlling means includes means responsive to transmission in either direction to render the repeater operative to transmit in that direction, transient currents returning to the repeater in either direction may cause the repeater to be rendered operative in that direction, whereupon at least a portion of the transient currents will be amplified by the repeater and transmitted in the other direction. After these currents have passed through the repeater, some will be returned to the repeater from the line into which they were last transmitted, and may cause the repeater to again become operative in the direction in which it first transmitted and transmit some of the transient energy to the line from which it was originally returned. Thus,

the repeater may be set into a kind of singing consisting of rapid and regular reversals of its direction of transmission. Even if the repeater be not set into sustained singing, there may be sufficient reflection of energy to cause it to reverse its direction one or more times. The effects of such reversals would depend upon the number of the reversals, the type of the repeater and other factors.

In accordance with the invention the repeater controlling means is made to have at the end of each period of uninterrupted transmission, a relaxation time, or period of insensitivity to energy entering the output side of the repeater, this relaxation time being made suitable for protecting the repeater from deleterious effects of transient kick-back or return of energy from the connected lines; for it has been discovered that, in general, it is possible to provide a sufficient relaxation time without causing undue loss in articulation because of interference with the ability of the transmission receiving station to break in or take control of the repeater with sufficient promptness upon cessation of transmission from the repeater into the line connected to that station.

It has heretofore been proposed, for example in John Mills Patent No. 1,434,790, November 7, 1922, to suppress echo currents in long two-wire circuits involving bilateral repeaters, that is, repeaters in condition at some one time to transmit in either direction, for instance, the ordinary or standard 22-type repeaters, by employing means which respond to transmission in one direction in the system in such manner as to cut off transmission in the other direction. In accordance with the present invention, a repeater which is never in condition, at any one time, to transmit in more than one direction, and which responds to transmission in one direction to condition the repeater for transmitting in only that direction, may be connected in a long two-wire circuit, either alone or in tandem with bilateral repeaters, to suppress echoes as well as to amplify the transmission in either direction; and where it is desired to reduce the number of possible echo paths or break up echoes other than those which would traverse the whole length of the circuit, a plurality of echo suppressing repeaters may be connected in the circuit, one at each point at which it is desired to stop the passage of echo currents. The nature and effects of echo currents have been explained by A. B. Clark in his article on Telephone transmission over long cables, Journal of the American Institute of Electrical Engineers, January 1923, page 1, and reference may be had to that article for a better understanding of the phenomena of echo effects.

Fig. 1 of the accompanying drawings is a circuit diagram of a repeater embodying

various features of the invention; Figs. 2, 4 and 5 are curves for facilitating explanation of the operation of the circuit of Figs. 1 and 3; Fig. 3 shows a modification of a part of the circuit of Fig. 1; Figs. 6 and 7 show two modifications of another part of the circuit of Fig. 1; Fig. 8 is a circuit diagram of a repeater embodying various features of the invention and employing only one speech amplifier and delay circuit; Fig. 9 shows a modification of a part of the circuit of Fig. 8; and Fig. 10 shows schematically how repeaters such, for example, as that shown in Fig. 1 or Fig. 9, can be employed for suppressing echoes in long two-wire circuits, which may have bilateral repeaters connected therein.

In Fig. 1 two lines 11 and 11' forming, for instance, part of a two-wire telephone transmission system, are interconnected by a repeater circuit comprising an east repeater 13 for transmitting from west to east and a west repeater 13' for transmitting from east to west, as indicated by the arrows. The repeater circuit also comprises the usual three-winding transformers or hybrid coils 15 and 15', and comprises resistances 17 and 17' in place of the impedance networks usually employed in a 22-type repeater for balancing the impedances of the lines between which the repeater is connected. Preferably, resistances 17 and 17' approximately balance the impedances of lines 11 and 11' respectively; but, for reasons which will be made apparent hereinafter, close balancing is not required. If desired, transformers 19 and 19' may be interposed between lines 11 and 11' and their hybrid coils, respectively, as shown.

The output circuit of repeater 13 includes the primary winding of a transformer 20. The secondary winding of transformer 20 is connected to one limb of a hybrid coil 21, another limb of which is connected to a resistance 22 for balancing the output impedance of the repeater 13. The series winding of the hybrid coil 21 is connected to feed into a delay circuit 25, described hereinafter, the delay circuit in turn feeding the series winding of the hybrid coil 15', that is the winding conjugate to the bridge circuit of the hybrid coil. If desired, a transformer 26 may be interposed between the delay circuit 25 and the series winding of hybrid coil 15', as shown.

The output circuit of repeater 13' includes the primary winding of a transformer 20'. The secondary winding of transformer 20' is connected to one limb of a hybrid coil 21', another limb of which is connected to a resistance 22' for balancing the output impedance of the repeater 13'. The series winding of the hybrid coil 21' is connected to feed into a delay circuit 25' similar to the delay circuit 25, the delay circuit 25' in turn feeding into the series winding of the hybrid coil 15. If

desired, a transformer 26' may be interposed between the delay circuit 25' and the series winding of the hybrid coil 15, as shown.

The output of the delay circuit 25 is normally short circuited through a lead 30, the armature and back contact of a relay 31, a lead 32, the armature and back contact of a two-winding relay 33, and a lead 34.

The output of the delay circuit 25' is normally short circuited through a lead 30', the armature and back contact of a relay 31', a lead 32', the armature and back contact of a two-winding relay 33', and a lead 34'.

The bridge circuit of the hybrid coil 21 preferably comprises the primary winding of a transformer 40, the secondary winding of which feeds an amplifier and filter 41 preferably comprising tandem connected electron tube amplifiers 42 and 43 feeding a high pass filter 44 having a cut-off frequency of the order of 500 cycles per second. The filter may be, for example, of the type shown in Fig. 6 of G. A. Campbell Patent No. 1,227,114, May 22, 1917. The filter 44 feeds a rectifier 45, preferably of the three electrode electron tube type, through a lead 46, the normally closed contact of a relay 50', a lead 51, the normally closed contact of a relay 52', a lead 53, and, if desired, a transformer as shown at 54. A condenser 55 having a capacity of the order of 0.1 microfarad is preferably connected across the output circuit of the rectifier, this output circuit including the winding of the relay 31 and also the winding of a relay 50.

The bridge circuit of the hybrid coil 21' preferably comprises the primary winding of a transformer 40', the secondary winding of which feeds an amplifier and filter 41' corresponding to the amplifier and filter 41. The amplifier and filter 41' feeds a rectifier 45', corresponding to the rectifier 45, through a lead 46', the normally closed contact of the relay 50, a lead 51', the normally closed contact of a relay 52, a lead 53', and, if desired a transformer as shown at 54'. The rectifier 45' includes a condenser (not shown), corresponding to the condenser 55, connected across its output circuit, and this output circuit comprises the winding of the relay 31' and also the winding of the relay 50'.

The right hand winding of the relay 52 and the left hand winding of the relay 33 are the operating windings of those relays, respectively, and are energized to operate those relays whenever relay 31 closes its front contact, the energizing circuit extending from a grounded battery 60 through the left hand winding, or operating winding, of the relay 33, the operating winding of the relay 52, the front contact of the relay 31, the lead 30, and a lead 61, to ground.

The left hand winding of the relay 52 is a holding winding, and is energized by a local battery 62 whenever the front contact of relay 33 is in the closed condition.

If desired, the right hand winding of the relay 33 may be short circuited by a switch 63, to retard the release of the armature of the relay, and a condenser with means for varying its capacity may be connected across the operating winding of the relay, as shown at 64, to retard the release of the armature of the relay.

The left hand winding of the relay 52' and the right hand winding of the relay 33' are the operating windings of those relays, respectively, and are energized to operate those relays whenever relay 31' closes its front contact, the energizing circuit extending from the grounded battery 60 through the right hand winding, or operating winding, of the relay 33', the operating winding of the relay 52', the front contact of the relay 31', the lead 30' and a lead 61', to ground.

The right hand winding of the relay 52' is a holding winding, and is energized by a local battery 62' whenever the front contact of relay 33' is in the closed condition.

If desired, the left hand winding of the relay 33' may be short circuited by a switch 63', to retard the release of the relay armature, and a condenser may be connected across the operating winding of the relay, as shown at 64', to retard the release of the relay armature.

The delay circuit 25 is shown, by way of example, as a low pass filter type of structure, such as that of Fig. 7 of G. A. Campbell Patent No. 1,227,114, May 22, 1917, "Electrical receiving, translating, or repeating circuit," comprising recurrent sections each having a series arm containing lumped inductance and a shunt arm containing lumped capacity. However, the delay circuits are here employed as means to delay the propagation of signaling currents therethrough, for reasons which will be made apparent hereinafter, and they need not necessarily have filtering properties, but may be circuits or means of any type suitable for producing the desired delay in the propagation of signals.

The delay circuit 25', like the delay circuit 25, is intended to represent any suitable means that may be employed for introducing a desired delay in the propagation of signals therethrough.

To reduce the effect of line noise upon the operation of the repeater, the grid potential of the rectifier 45 should preferably be set so that a definite minimum alternating current input to the rectifier will be required before the relay 31 or the relay 50 gets sufficient rectified input to be operated; for if, instead, it be attempted to protect relay 31 or relay 50 against line noises below a given minimum by biasing the relay, as for instance by a biasing current in an auxiliary winding (not shown) on the relay, then, noise energy being amplified in substantially the same ratio as speech energy, substantial gain in the speed

of operation of the relay is not readily obtained by increasing the driving or operating energy, since the biasing current must be correspondingly increased. Where the desired 5 margin against noise is secured by choking off the noise energy before it reaches the relay circuit, the speed of operation of the relay can be made high by applying a high value of driving or operating energy thereto.

10 Were the filter 44 and the condenser 55 omitted from the circuit, currents of frequencies in the neighborhood of the mechanical resonance frequencies of the tongues of relays 31 and 50 would tend to cause chattering of 15 these tongues when they should be held in their operated positions by the relay windings, and, further, low frequency noise currents, for instance, cross-ringing, Morse thump, and power interference, which are 20 likely to be greater in magnitude than the voice currents themselves, might deleteriously affect the operation of the relays. The filter 44 prevents such disturbing currents from entering the rectifier, and the condenser 55 25 diminishes the amplitude of the high frequency components of the rectified currents so that any alternating constituents of the current reaching the relays will not be sufficiently powerful to cause chattering of the 30 relays. It has been found that since a chatterless make of the relays is not required, the condenser 55 can be made to effect sufficient smoothing out of the rectified current with only very slight delay in the propagation of 35 the rectified current to the relays.

The characteristics and functioning of the amplifier and filter 41', and of the rectifier 45' are similar to those of the amplifier and filter 41 and of the rectifier 45, respectively.

40 The operation of the system in repeating from west to east will now be described, and its operation in repeating from east to west, which is similar, will be apparent from this description.

45 Part of the transmission from line 11 passes to the input of repeater 13 and part is lost in the short circuit extending from the secondary winding of transformer 26' through leads 30' and 34' and the back contacts of relays 31' and 33'. A part will also be lost in resistance 17. Part of the output of repeater 13 is transmitted through hybrid coil 21 and amplifier and filter 41, to rectifier 45, which operates relays 31 and 50. The operation of relay 31 places a gap 55 in the short circuit which extended across the primary winding of transformer 26 through leads 30 and 34 and the back contacts of relays 31 and 33. Thus, the operation of relay 31 enables transmission to pass onto hybrid coil 15' and thence to line 11'. At the same time relay 50 has placed a gap 60 in the output circuit of the amplifier and filter 41', which will prevent the amplified transmission coming into the input of re-

peater 13' from operating relay 31' to render the repeating path west operative by opening the above traced short circuit across the primary winding of transformer 26', or from operating relay 50' to open the output circuit of the amplifier and filter 41.

65 By providing the delay circuit 25, the above traced short circuit across the primary winding of transformer 26 may be opened before the transmission from repeater 13 reaches it, 75 thus avoiding any loss of the beginning of a word due to time taken in switching. If desired the delay circuit may be designed to compensate for only a part of the loss of a word that would, in the absence of the delay 80 circuit, result from the time taken for switching. Further, the possibility of trouble in case the operation of relay 31 is by chance quicker than that of relay 50, is eliminated by the delay circuit, since the delay circuit 85 insures that relay 50 will begin to operate an appreciable time before any possible starting of the operation of relays 31' and 50'.

Upon cessation of transmission from line 11, or when transmission falls below a predetermined energy level, relays 31 and 50 release. The value of this predetermined level is dependent upon the energy level of line noise or external disturbances to which the system is subject, and upon what margin or degree of protection against such disturbances it is desired to afford the system. In practice, there is a tendency for the release of relay 31 to cut off the transmission of the last syllable of words ending weakly, 90 such as those with the final syllables "ly" and "ing". Relay 33 acts to reduce this terminal clipping in the following manner. As has been indicated above, when relay 31 closes 95 its front contact in response to transmission from line 11, it causes relay 33 to place a gap in the above traced short circuit across the primary winding of transformer 26, this gap being in series with the gap produced at the back contact of relay 31. Therefore, when 100 the energy level of the transmission from line 11 falls to such a value that relay 31 releases, opening the operating circuit of relay 33 at the front contact of the relay 31 and closing the gap at the back contact of 105 the relay 31, the short circuit across the primary winding of transformer 26 remains open at the back contact of relay 33 until that relay, which is slow operating due to 110 the condenser 64 (and the right hand or short circuited winding of the relay, if switch 63 is closed), releases its armature and closes 115 its back contact.

Another advantage which follows from the use of relay 33 is that if two of the syllables 125 coming from line 11 are separated by an interval shorter than the time required for relay 33 to close its back contact, the second syllable will find the repeater circuit already operated—temporarily biased in its favor—and 130

hence there would be no tendency toward initial clipping of this syllable.

As indicated above, when relay 31 closes its front contact in response to transmission from line 11, it causes relay 52 to place a gap in the output circuit of the amplifier and filter 41', this gap being in series with the gap produced at the back contact of relay 50. Therefore, when transmission from line 11 ceases, or when the energy level of that transmission falls to such a value that the relays 50 and 31 release, the relay 31 opening the circuit of the operating winding of relay 52 at the front contact of the relay 31 and the relay 50 closing the gap at the back contact of the relay 50, the output circuit of the amplifier and filter 41' remains open at the back contact of relay 52 until that relay releases and closes its back contact. The release of relay 52 is delayed by its left hand winding or holding winding, the local circuit of which remains closed until the armature of the slow release relay 33 has moved away from the front contact of the relay 33. The speeds of release relays 33 and 52 are so adjusted that, at the contact of relay 52, the output circuit of the amplifier and filter 41' remains open for a short interval of time after the last transmission from line 11 which caused relays 31 and 50 to remain operated has passed through the delay circuit 25 and onto line 11'. During this interval the repeater circuit is not responsive to energy incoming from line 11'. The provision of this time interval, or relaxation time, is to insure that energy transmitted from hybrid coil 15' into line 11' and returning from line 11' to hybrid coil 15' either in amplified or unamplified form, cannot reverse the repeater, nor cause the repeater to sing between the lines 11 and 11' due to sustained repetition of such reversals in the manner referred to above.

Various factors must be considered in determining what is a proper time interval to be employed as a relaxation time. If the interval is too long, it will unduly interfere with the ability of the listener to break in on the speaker, or it may even happen that the first part of a quick reply will be cut off. If the interval is too short, the energy level of the transient energy returning to the repeater from the line will, at the end of the period, be sufficiently high to cause reversal of the repeater. The energy level of the returning transient energy at any given instant will depend upon the magnitude of the last repeated energy and the condition of the line into which it was repeated. For any given energy level of the returned transient at the end of the relaxation period, the likelihood of reversal of the repeater by the transient will depend upon how long, after the period of insensitivity, the means controlling the repeater switching means requires to attain a condition in which the subsequent operation of the

switching means is assured. With a circuit of the type shown in Fig. 1, a switching time of less than .003 second has readily been attained. By the switching time is meant the total time required for ordinary voice transmission to switch the repeater from the normal or neutral condition to the condition for repeating in one direction or the other. The likelihood of the occurrence of repeated reversals or singing will further depend upon this switching time, or the total time taken, after the period of insensitivity, to switch the repeater and also upon the condition of the line into which the repeater feeds when first reversed by transient energy, and the magnitude of the energy so fed into that line. It is entirely possible that even though single reversals from reflected energy would not take place with the transmission of ordinary speech, a large impulse such as would result from the operation of the subscriber's switchhook might set the system off into repeated reversals or singing.

Extensive experiments have shown that in a circuit not including any bilateral repeaters, that is, repeaters conditioned to repeat in opposite directions simultaneously, a relaxation period of the order of .02 or .03 second is, under ordinary conditions, sufficient to prevent returned transient energy from causing reversal or singing of the repeater. Should any bilateral repeaters be included in the circuit this relaxation time would have to be increased to a value of the order of double this value, the exact requirement as to minimum permissible relaxation time depending upon the individual case.

The shortest pause of a speaker which will permit the listener to gain sufficient control of the repeater to insure that the repeater will be reversed, is longer than the relaxation time of the repeater, or in other words, is longer than the period of insensitivity of the repeater controlling means to energy entering the output side of the repeater upon the cessation of the energy output of the repeater to the line. Consequently, serious interference with the carrying on of conversation can be avoided only if the minimum permissible relaxation time of the repeater is less than the longest silent interval that, in ordinary speech, occurs as often as it is required that the listener be able to break in on the speaker. It has been discovered by extensive experiment, that in ordinary speech, silent intervals (or intervals when the energy level of the speech is so low that the effect of the speech in preventing the listener from reversing the pointing of the repeater is negligible) longer than the minimum permissible relaxation time of the repeater do occur as frequently as it is required, for satisfactory conversation, that the listener be able to break in upon the talker. It has been determined that satisfactory ease

of break can be secured if the relaxation time of the repeater is of the order of .05 second.

Since a relaxation time of the order of .02 or .03 second is sufficient to prevent transient return energy from causing reversal or singing of the repeater in a circuit involving no bilateral repeaters, and since satisfactory ease of break can be secured with a relaxation time as great as .05 second, a relaxation time of about .03 second may be employed as practicable for such a circuit.

The back contact of relay 33 should close slightly before that of relay 52, so that the repeater path east will be rendered inoperative before the repeater path west can be rendered operative and there will therefore be no possibility of singing of the repeater due to both of these paths being operative at the same time. Since these two paths are never operative at the same time, the resistances 17 and 17' need not accurately balance the impedances of lines 11 and 11', respectively, in order to prevent the repeater from singing. Neither is it necessary that such balancing be accurate in order to insure that energy from line 11 will divide between the other three impedances connected to hybrid coil 15 in such manner that a satisfactory proportion of the energy will enter the repeater 13. It may be here noted that if resistance 17 accurately balances line 11 the short circuit across the lower winding of transformer 26' by means of relays 31' and 33' will not affect the input from line 11 to the repeater 13. If the balance is not accurate this short circuit will produce some effect on the input to the repeater, but still none of importance.

It has been found that reduction of interference between the two branches of the circuit of Fig. 1 is attained by locating the relay breaks in the amplifier rectifier systems on the grounded sides of those systems, as shown at the contacts of relays 50, 50', 52 and 52' in Fig. 1, instead of on the ungrounded sides of those systems.

In Fig. 2 the full line curve is an effective resistance-frequency curve, and the dotted curve is an impedance-frequency curve, typical of a delay filter such as 25 with its output short circuited as is normally the case in the circuit of Fig. 1. The vertical arrows indicate, approximately, natural frequencies of the short circuited delay circuit, and these frequencies give steady state impedance minima and therefore would give maxima of steady state input current for constant amplitude of voltage applied to the input of the delay circuit; but, as explained hereinafter in connection with Figs. 4 and 5, when a voltage of any one of these frequencies is suddenly applied the current which flows into the delay circuit rises to its final or steady state value slowly, in the manner indicated in Fig. 4. Therefore, if the input

of the delay circuit and the primary winding of the transformer 40 were serially connected to each other directly across the secondary winding of transformer 20, and the hybrid coil 21 were omitted from circuit, then, for any one of these frequencies, the input to transformer 40, and hence the rectified current applied to the relays 31 and 50, would rise to its final value slowly, and consequently the relays would be slow operating for any of these frequencies, since the sensitivity of the relays must be kept low enough to insure that they will not be operated by the steady state value of relay currents due to noise currents of these frequencies. For any frequency midway between frequencies indicated by adjacent vertical arrows in Fig. 2, the final value of the current flowing into the short circuited delay circuit would be small, but the current would rise rapidly to a value even exceeding the final value, in the manner indicated in Fig. 5. If the input of the short circuited circuit and the primary winding of the transformer 40 were connected in parallel directly across the secondary winding of transformer 20, the hybrid coil 21 being omitted from circuit, then as explained hereinafter in connections with Figs. 4 and 5, for any one of the frequencies indicated by vertical arrows in Fig. 2 the input to the transformer 40 would rise quickly to a value higher than its final or steady state value, in the manner indicated in Fig. 5, but for any frequency midway between the frequencies indicated by adjacent vertical arrows in Fig. 2 the current in the transformer 40 would rise slowly to a high steady state value. Therefore, in the case of either the series or the parallel connection of the transformer 40 and the short circuited delay circuit, the speed of operation of both relays 31 and 50 would be different for different frequencies of voltage applied to hybrid coil 15 by line 11, and therefore would be different for different syllables coming into the repeater from line 11.

When the primary winding of transformer 40 and the input of the delay circuit 25 are connected to the secondary winding of transformer 20 through the hybrid coil 21 instead of directly, so that the impedance of the delay circuit is in conjugate relation to the primary winding of transformer 40 or circuit which supplies energy to the relays 31 and 50, the impedance of the delay circuit will not affect the amount of the current which flows to the relays at any frequency. As it has no effect at any frequency, it can have no transient effect. Therefore, by thus employing the hybrid coil 21, the speed of operation of the relays can be equalized for different frequencies, and yet the energy for controlling the relays can be picked off from the main transmission circuit at the output side of the speech amplifier 13, so that

more energy will be available than if the energy were picked off from the input side of the amplifier and lower amplification can be employed in the amplifier-rectifier 41-45.

5 Moreover, where an amplifier-rectifier is bridged across a circuit for abstracting speech energy, for instance in order to control a switching relay, the abstracted energy is generally stepped up to as high a voltage 10 as practicable, with the danger of driving the grid of the first tube decidedly positive. In such cases a degradation of speed being transmitted may occur, due to the introduction of harmonics. By employing a balanced 15 coil, as that at 21 in Fig. 1, such harmful reaction can be prevented. As the amplifier-rectifier is in conjugate relation to the outgoing circuit carrying the main transmission, any harmonics generated in the amplifier rectifier circuit are balanced out from that outgoing circuit.

In Fig. 1 the repeater 13, the hybrid coil 21 and the delay circuit 25, are shown as comprised in a block 66, and in Fig. 3 is shown a 25 block 66^a which may be substituted for the block 66 in Fig. 1. In the block 66^a no hybrid coil corresponding to the hybrid coil 21 of Fig. 1 is employed. The delay circuit 25 is connected to the repeater 13 through the 30 transformer 20, and also through a transformer 67. A transformer 40'', the secondary winding of which feeds the amplifier-rectifier 41-45 (not shown in Fig. 3) just as the secondary winding of transformer 40 of 35 Fig. 1 feeds that amplifier-rectifier, has a primary winding 68 connected across the circuit between transformers 20 and 67 and has a primary winding 69 connected across a resistance 70 which is serially connected in that 40 circuit. The steady state impedance of the short circuited delay circuit passes through wide variations (see Fig. 2) as the frequency changes, and correspondingly its transient impedance, and at each of the low impedance 45 points in the range of applied frequencies that is, at each frequency such as those indicated by the vertical arrows in Figs. 2) the current entering the delay circuit, and consequently the voltage across winding 69, varies in the general fashion indicated in Fig. 50 4, whereas when a voltage of any frequency midway between those indicated by adjacent vertical arrows in Fig. 2 is suddenly applied the current entering the delay circuit, and therefore the voltage across winding 69, varies in the general fashion indicated in Fig. 5. However, when the current entering the delay circuit varies as in Fig. 4, the voltage 55 across the delay circuit, and therefore across winding 68, will vary in the general fashion indicated in Fig. 5, wherein the time scale is the same as in Fig. 4; and when the current entering the delay circuit varies as in Fig. 5, the voltage across the delay circuit, and therefore across winding 68, will vary in the

general fashion indicated in Fig. 4. Consequently, by combining the fluxes produced by windings 68 and 69 in transformer 40'', the voltage wave applied to the amplifier-rectifier 41-45 by the secondary winding of 70 transformer 40'' can be made to be of approximately the same form as that applied to hybrid coil 15 by line 11.

In Fig. 1 there is shown a block 73 comprising the transformer 26, hybrid coil 15', 75 resistance 17' and transformer 19'. In Fig. 6 there is shown a block 73^a which may be substituted for the block 73 in Fig. 1. Leads 74', 75', 76, 61, 34 and 30 in Fig. 6 are the same as correspondingly designated leads in 80 Fig. 1. Leads 76 and 61, which are the output leads from the delay circuit, may be short circuited by the circuit through leads 30 and 34 and the back contacts of relays 31 and 33 (not shown in Fig. 6), if a short section of artificial line, indicated as 80 in Fig. 6, be inserted between the short circuited and the junction of the input of repeater 13' with line 11'; for the artificial line 80 will prevent the short circuit from also short circuiting the input of repeater 13' with respect to line 11'.

The portion of the circuit of Fig. 1 which is included in the block 73 may also be replaced by a circuit of the form shown in the block 73^b in Fig. 7. In the latter figure, the transformer 26 feeds into line 11' through a balanced bridge 85, instead of through a hybrid coil as in Fig. 1. One side of the bridge comprises a resistance 88 and a secondary 100 winding 89 of a transformer which has its primary winding fed from the transformer 26; and the other side of the bridge comprises a resistance 90, preferably equal to resistance 88, the circuit which extends through lead 30, thence through the back contacts of relays 33 and 31 (not shown in Fig. 7), and thence through lead 34, and a winding 91, preferably having the same number of turns as winding 89. Normally the bridge is in 105 the balanced condition and currents fed into it from transformer 26 produce no voltage across line 11'; but whenever the last mentioned side of the bridge is open at the back contact of relay 31 or of relay 33, the bridge 110 is unbalanced, and will transmit from transformer 26 to line 11'.

Fig. 8 shows a modification of the circuit of Fig. 1 employing but a single speech amplifier and delay circuit. The speech amplifier is shown at 13 and repeats in both directions between lines 11 and 11'. The repeater 13 and the lines 11 and 11', and also elements 15, 15', 17, 17', 31, 31', 50 and 50' in Fig. 8 are the same as in Fig. 1. Relay 152 in Fig. 120 8 has its operating winding in series with the front contact of relay 31 and its contact in series with the contact of relay 50, just as has the relay 52 in Fig. 1, and is a slow release relay although the circuit of Fig. 8 125 130

has not been shown as provided with any relay corresponding to the relay 33 of Fig. 1. Similarly, relay 152' in Fig. 8 has its operating winding in series with the front contact of relay 31' and its contact in series with the contact of relay 50', just as has the relay 52' in Fig. 1, and is a slow release relay although the circuit of Fig. 8 has not been shown as provided with any relay corresponding to the relay 33' of Fig. 1. Amplifier-rectifiers 95 and 95' in Fig. 8 correspond to the amplifier-rectifiers 41-45 and 41'-45', respectively, of Fig. 1, but may, if desired introduce greater amplification, to make up for the fact that the input to amplifier-rectifiers 95 and 95' is obtained directly from the hybrid coils 15 and 15', respectively, without amplification.

A balanced bridge 96, which can be balanced quite closely, enables transmission from either line 11 or 11' to be supplied to the input of repeater 13 without getting over to the other line.

The operation of the circuit in transmitting from west to east will now be described, and this will make apparent the operation in transmitting from east to west, which is similar.

The output of the repeater 13 is normally short circuited at the contact of relay 31 and also at the contact of relay 31'; but, as pointed out in connection with Fig. 1, the short circuiting of the series windings of the hybrid coils 15 and 15' does not materially interfere with the supply of energy from lines 11 and 11' to the bridge circuits of the hybrid coils 15 and 15' respectively.

Speech coming from line 11 will start through the bridge 96, repeater 13 and delay circuit 25. At the same time, amplifier-rectifier 95 will cause relays 31 and 50 to attract their armatures. The operation of relay 50 cuts amplifier-rectifier 95' out of circuit so that relay 31' and 50' can not be operated and cuts the input of bridge 96 and repeater 13 off from line 11'. The opening of the back contact of relay 31 permits amplified speech currents to pass from transformer 26 to hybrid coil 15' and line 11'. If the delay circuit time is made to cover the time required to open the back contacts of relays 31 and 50, there will be no danger of improperly operating relays 31' and 50' or setting up a local singing circuit. The closing of the front contact of relay 31 causes the operation of relay 152 through a local energizing circuit.

When transmission from line 11 ceases, relays 31, 50 and 152 releases, but the latter relay maintains its contact open for a predetermined time to protect the system against transient kick-back of energy from line 11'. The time of closing of this relay 152 is made sufficiently great to give the system a relaxation time of a value such as is specified above for the system of Fig. 1. The relay 31

should close its back contact before relay 152, so that there will be no possibility of local singing, especially since, as indicated above, the resistance 17' will not ordinarily be a close balance for the impedance of line 11'.

If desired relays corresponding to the relays 33 and 33' of Fig. 1 may, of course, be incorporated in Fig. 8, to delay closure of the short circuits controlled by relays 31 and 31' respectively and thus reduce terminal clipping of words, and to delay release of relays 50 and 50' respectively.

Instead of employing the hybrid coils 15 and 15' in Fig. 8 to prevent the short circuits across the output of the repeater 13 from materially interfering with the supply of energy from lines 11 and 11' to the input of the repeater, artificial lines (not shown in Fig. 8) may be employed, after the fashion in which, as pointed out above, the artificial line 80 of Fig. 6 may be employed instead of the hybrid coil 15' in Fig. 1.

Fig. 9 shows a circuit which may be substituted for the balanced bridge 96 in Fig. 8, to connect the input of the repeater 13 to the bridge points of the hybrid coils 15 and 15'. This circuit comprises an amplifier 110, preferably of the electron discharge type, fed from the bridge points of the hybrid coil 15 (not shown in Fig. 9) through the back contacts of relays 50' and 152' (not shown in Fig. 9) and leads 111 and 112, and in turn feeding into the speech amplifier 13 (not shown in Fig. 9); and the circuit also comprises an amplifier 110' fed from the bridge points of the hybrid coil 15' (not shown in Fig. 9) through the back contacts of relays 50 and 152 (not shown in Fig. 9) and leads 111' and 112', and in turn feeding into the speech amplifier 13 (not shown in Fig. 9). Since the amplifiers 110 and 110' are unidirectionally transmitting devices, they allow energy to be supplied from either line, 11 or 11', to the input of repeater 13, but prevent that energy from getting over to the other line without passing through the repeater 13, the delay circuit 25 and the series winding of the hybrid coil 15 or 15' connected to that other line.

Fig. 10 shows a long two-wire circuit, for instance a telephone transmission line, re-peated with one or more bilateral repeaters 210, for example ordinary or standard 22-type repeaters such as that shown in Figs. 10 or 11 of G. A. Campbell Patent No. 1,227,114, May 22, 1917. One or more unilateral, voice operated repeaters 215, which may be, for example, a repeater of the type shown in Fig. 1 or of the type shown in Fig. 8, are also connected in the line 210. The dotted lines at each side of the repeaters are to indicate that the repeaters may be electrically or geographically remote from each other and from a subscriber's station 215 at the west end of the

line 200 and a subscriber's station 216 at the east end of the line.

Each repeater 215 may have its relaxation time adjusted, as pointed out in connection with the circuit of Fig. 1, to prevent energy returned or fed back into the repeater from the line from reversing the point of the repeater. Therefore, the repeater will suppress echo currents, since the repeater, after transmitting in one direction, must have its pointing reversed before it is capable of transmitting in the other direction. As explained in connection with the circuit of Fig. 1, the relaxation time of the repeater should be made sufficiently great to take care of the longest period of appreciable returned energy or the longest echo of objectionably high volume or energy level, but should not be sufficiently long to cause undue interference with the ease with which a listener can break in upon a speaker.

Operating a relay from energy of a current having high and low frequency components by separating the high frequency components from the low frequency components, rectifying the high frequency components alone, removing current fluctuations of said high frequency from the rectified current, and applying the resultant current to the relay, is claimed in R. V. L. Hartley Patent 1,588,186, June 8, 1926, assigned to the assignee of this application.

Rendering a voice controlled repeater operative to transmit in the desired direction immediately upon the openings of switch contact, the opening of the contact being accomplished in response to voice currents and without delay due to other mechanical movement, is claimed in W. S. Gorton application Serial No. 658,514, filed August 21, 1928, assigned to assignee of this application.

The application of a delay circuit to a voice controlled repeater to delay transmission until the voice operated switching means has had time to operate is claimed in H. D. Arnold Patent 1,565,302, December 15, 1925. Two-way repeater circuits, assigned to the assignee of this application.

The general principles herein disclosed may be embodied in many organizations widely different from those specifically illustrated and described without departing from the spirit of the invention defined in the appended claims.

Although the invention has been set forth with especial reference to its application to the repeating of voice frequency currents, it is of course also applicable to the transmission and repeating of currents of other frequencies, whether higher or lower, as for instance currents of the frequencies commonly used for radio and carrier currents.

The expression "unilateral means," as used in the claims, refers to means never in condition, at any one time to transmit in more

than one direction, as distinguished from bilateral means, which are means in condition, at some one time to transmit in either direction.

The invention claimed is:

1. The method of operating a current transmission device connected in a circuit and subject to being rendered operative to transmit in a given direction in said circuit by transmission returning from said circuit to said device, which comprises preventing said returning transmission from so affecting said device.

2. In a signal transmission system, a signal transmission path comprising a normally closed switch contact in that condition directly reducing the transmission efficiency of the path, and means for translating received signaling variations into mechanical movement, and for directly mechanically employing the initial movement so produced, at its inception, to open said switch contact.

3. In combination, a circuit comprising a current transmission path, means including a closed switch and decreasing the transmitting efficiency of said path while said switch is closed, means for translating the current variations received over said path into mechanical movement, and for mechanically employing the initial movement so produced, at its inception, to open said switch, and thereby causing increase in the transmitting efficiency of said path, and means for delaying transmission in said path until said switch has opened.

4. A circuit comprising two transmission paths, means, comprising a closed switch, shunting one of said paths and decreasing the transmitting efficiency of said path, means for opening said switch in response to transmission in said circuit, and means for rendering said transmission responsive means insensitive for a predetermined time after said other path has ceased transmitting.

5. The method of operating a current transmission path and a circuit controlling device having parts so movable with respect to each other as to increase the impedance of said device, which comprises causing alternating signaling currents to flow in said path, rectifying said alternating currents, causing said parts to so move in response to flow of said rectified currents and without delay to other mechanical motion, and increasing the transmission efficiency of said path immediately upon the consequent increase of impedance of said circuit controlling device.

6. A circuit comprising a two-way current transmission device and means responsive to flow of transmission in either direction in said circuit for rendering said device operative to transmit, but insensitive to flow of transmission in one direction in said circuit for a predetermined time after said device

has ceased transmitting in the opposite direction substantially just sufficient to prevent return of transmission to said device from rendering said device operative to transmit.

7. A circuit, a two-way unilateral repeater connected therein, means at said repeater responsive to transmission of a given energy level in one direction in said circuit for rendering said repeater operative to transmit in said direction in less time than the time required for energy fed from said repeater to said circuit in the opposite direction to return to said repeater and there decrease to an energy level of the order of said first mentioned level, and means for preventing said returned energy from deleteriously affecting the operation of said transmission responsive means.

- 20 8. In a transmission system, a transmission path, means forming normally substantially a short-circuit path across said transmission path, and means responsive to transmission at a part of said system other than said short-circuit path for causing the opening of said short-circuit path while permitting transmission over said transmission path.

9. In combination, two unidirectionally transmitting amplifiers each having an input circuit and an output circuit, a closed transmission circuit connecting the output circuit of one of said amplifiers to the input circuit of said other amplifier, a closed transmission circuit connecting the output circuit of said other amplifier to the input circuit of said one amplifier, and means preventing local singing of said amplifiers, said means comprising a normally closed switch contact in one of said transmission circuits and depending upon the closed condition of said contact for preventing said singing.

10. In combination, a circuit comprising a current transmission path, a device normally decreasing the transmitting efficiency of said path, said device having parts so movable as to increase its impedance, means so moving said parts in response to transmission in said circuit and without delay due to other mechanical movement, and means for delaying flow of transmission to said path until said parts have thus been moved.

11. In combination, a circuit comprising a current path, a relay having an armature, said armature in the normal unenergized condition of said relay closing a short circuit decreasing the transmitting efficiency of said path, means for translating signaling variations into current variations for actuating said relay to control said armature to open said short circuit, the opening of said short circuit increasing the transmitting efficiency of said path, and means for delaying passage of said transmission to said path until said switch has opened.

12. A circuit comprising two oppositely

directed unidirectional transmission paths, a switch having contacts in one transmission path which when closed decreases the transmission efficiency of said one path, means for translating signaling variations received over said one path into mechanical movement, and for mechanically employing the initial movement so produced, at its inception, to open said switch contacts, and thereby increasing the transmitting efficiency of said path upon the opening of said switch contacts, and means for rendering said transmission responsive means insensitive for a predetermined time after the other of said paths has ceased transmitting.

13. In combination, a current transmission path, a circuit controlling device having its parts so movable relatively to each other as to increase the impedance of said device, means for rectifying speech variations received over said path, means for converting the energy of the rectified speech variations into mechanical movement, and for mechanically employing the initial movement so produced, at its inception, for operating said movable parts to increase the impedance of said device, and means responsive to said increase of impedance for immediately increasing the transmission efficiency of said path.

14. A transmission network comprising a repeating path, a switch in its closed condition reducing the transmitting efficiency of said path, means for rectifying speech variations, means for converting the energy of the rectified speech variations into mechanical movement and for mechanically employing the initial movement so produced, at its inception, to open said switch thereby increasing the transmitting efficiency of said repeating path.

15. In combination, a circuit comprising a current transmission path, means operative in response to transmission in said circuit for increasing the transmission efficiency of said path, and means for maintaining said increased efficiency after said first mentioned means assumes its unoperated condition.

16. In combination a circuit comprising a current transmission path, means operative in response to transmission in said circuit for rendering said path operative to transmit, and a relay controlled by said means for maintaining said increased efficiency after said first mentioned relay has returned to its unoperated condition.

17. In combination, a circuit comprising a current transmission path, a closed switch decreasing the transmission efficiency of said path, means for translating a portion of signaling variations received over said path into mechanical movement, and for mechanically employing the initial movement so produced, at its inception, to open said switch, and thereby increasing the transmitting efficiency of said path upon the opening of said switch,

- and means for maintaining said path at said increased efficiency for a predetermined time after said switch has closed due to cessation of the supply of signaling variations to said path.
18. The method of reducing echo effects in a transmission circuit repeatered with bilateral repeaters, which comprises maintaining said system normally inoperative to repeat from either end of the circuit to the other, and upon flow of transmission in either direction in said circuit conditioning said circuit for transmitting in that direction, and holding it conditioned in that direction for a predetermined time after said transmission has ceased.
19. A telephone transmission system comprising a two-way unilateral repeater and a bilateral repeater in tandem.
20. A telephone transmission system comprising a normally inoperative, transmission controlled, two-way unilateral repeater and a bilateral repeater in tandem.
21. A current transmission system comprising bilateral repeaters and a transmission controlled, echo-suppressing unilateral repeater in tandem, said repeaters being geographically remote from each other, and said unilateral repeater having a relaxation time at least as great as the time required for the longest echo which said unilateral repeater is to suppress to pass from the repeater to the reflecting point and back to the repeater.
22. A circuit, an impedance for approximately balancing the impedance of said circuit, two unidirectional current paths, a hybrid coil connecting said paths to said circuit and said balancing impedance and in conjugate relation to each other, one of said paths transmitting toward said coil and the other path transmitting from said coil, a switch short circuiting said coil with respect to said one path, and means for opening said switch in response to flow of transmission in said one path.
23. A circuit, two transmission paths connected to one end of said circuit, means substantially short circuiting one of said paths for preventing transfer of energy between said paths, means for transmitting to said circuit energy flowing towards said paths, and means for avoiding great loss of energy in transmitting from said circuit to said other path.
24. In combination, a line, two unidirectionally transmitting amplifiers therein, each having an input circuit and an output circuit, a short circuit across the output circuit of each amplifier for preventing local singing of the amplifiers, and a hybrid coil at the output side of each amplifier for avoiding great loss of incoming energy between the line and the input circuit of the other amplifier.
25. In combination, a circuit comprising a current path including a normally balanced bridge decreasing the transmitting efficiency of said path, said bridge including a switch for controlling the balancing thereof, and means responsive to transmission in said circuit for controlling said switch.
26. In combination, a line, two unidirectionally transmitting amplifiers therein, each having an input circuit and an output circuit, a short circuit across the output circuit of each amplifier for preventing local singing of the amplifiers, and an impedance line at the output side of each amplifier for avoiding great loss of incoming energy between the line and the input circuit of the other amplifier.
27. In combination, in a transmission circuit and incoming line, an outgoing line, an energy abstracting device tending to introduce harmonics into the circuit, a net work simulating the impedance of the incoming line, and a bi-conjugate network associating all of said elements together so that the incoming line and its network are conjugate, and the harmonic producing device and the outgoing line are conjugate.
28. In combination, a unidirectionally transmitting circuit, an impedance balancing network therefor, a reactance, a voice current responsive switch, an operating circuit for said switch, and means so interconnecting said first circuit, said balancing network, said reactance and said operating circuit that said reactance and said operating circuit are conjugate to each other.
29. In combination, an amplifier, an impedance for balancing the impedance presented by the output side of said amplifier, a reactance, a voice operated switch, an operating circuit for said switch, and means so interconnecting said output side of said amplifier, said balancing impedance, said reactance and said operating circuit that said reactance and said operating circuit are conjugate to each other.
30. In combination, a switch, an operating circuit therefor, a unidirectionally transmitting circuit comprising a filter and means for connecting the input end of said operating circuit in conjugate relation to the input end of said filter.
31. In combination, a unidirectional circuit comprising an incoming line and an outgoing line, and a rectifier circuit comprising branches connected in serial relation and in shunt relation, respectively, to said first circuit.
32. In combination, a circuit comprising a unidirectionally transmitting path, means responsive to flow of transmission in said circuit for rendering said path operative, at different times, to transmit in both directions, in said circuit, whereby two-way transmission may be had, and means for preventing transmission returning from said circuit

to said path from operating said transmission responsive means.

33. A transmission system comprising in combination, a circuit, a plurality of transmission paths connected thereto, each including a closed switch contact in that condition directly reducing the transmission efficiency of that path, and means for translating signaling variations received over one of said 10 paths into mechanical movement, and for directly mechanically employing the initial movement so produced, at its inception, to open a selected one of said contacts thus increasing the transmitting efficiency of the 15 corresponding path.

34. In combination, a unidirectionally transmitting path, two circuits for feeding signaling waves into said path, and means connecting said circuits to the input end of 20 said path and in conjugate relation to each other.

35. In combination, a unidirectionally transmitting path, two circuits for feeding signaling waves into said path, and a balanced bridge circuit connecting said circuits to the input end of said path and in conjugate relation to each other.

36. A system comprising a source of current having a relatively low frequency component and a relatively high frequency component, a rectifier, a filter for suppressing

said low frequency component connected between said source and said rectifier, a translating device fed by said rectifier, and non-inductive means connected to the output circuit of said rectifier for smoothing out said rectified current. 35

37. A system comprising a source of current having a relatively low frequency component and a relatively high frequency component, a rectifier, a filter for suppressing said low frequency component connected between said source and said rectifier, a normally closed direct current relay operative to open its contact in response to current from 45 said rectifier, and means connected to the output circuit of said rectifier for smoothing out said rectified current, said means consisting solely of a condenser. 40

38. In combination, a transmission circuit, 50 subject to noise currents, a direct current electromagnetic relay, an electron discharge rectifier fed from said circuit and feeding said relay, said rectifier comprising a control electrode and means maintaining said electrode at such a potential that said noise currents cannot be propagated through said rectifier. 55

In witness whereof, I hereunto subscribe my name this 2nd day of October A. D., 1923.

ROBERT C. MATTHES.
